R. MONTGOMERY.

MACHINERY FOR MAKING CORRUGATED BEAMS.

No. 10,549.

Patented Feb. 21, 1854.

UNITED STATES PATENT OFFICE.

RICHD. MONTGOMERY, OF NEW YORK, N. Y.

CORRUGATING METAL PLATES.

Specification of Letters Patent No. 10,549, dated February 21, 1854.

To all whom it may concern:

Be it known that I, RICHARD MONTGOMERY, of the city, county, and State of New York, have invented certain new and useful Improvements in Machinery for Making Corrugated Beams of Sheet Metal, of which the following is a full, clear, and exact description, reference being had to the accompanying drawing of the same, making part of this specification, in which—

Figure 1 represents a plan of machinery embracing my improvements; Fig. 2 represents a longitudinal section through the front or feed rolls; Fig. 3 represents a transverse section taken at the line $x-x$ of Fig. 1, showing a plate for a beam in its passage through the rolls and dies, where the depth of the folds is shallowest; Fig. 4 a transverse section through the crimping dies at the line $\#-\#$ of Fig. 1, where the depth of the folds is greatest; Fig. 5 an elevation of the crimping die detached, showing the configuration and bell-mouthed shape of the entrances to the spaces, in passing through which the plate is crimped; and Fig. 6 a longitudinal section of the crimping dies at the line 3, 3, of Fig. 1, showing the configuration of the spaces at the rear or delivery side of the dies. The dotted red lines in the two last figures show the diminution in the width of the space from the bell mouth to the rear side of the die; while the increased height of the spaces, corresponding to the diminution in their width, is shown in Figs. 3 and 4.

My improved method of operation consists in passing a plate a number of times through a pair of grooved rolls, and a stationary crimping die, by which the folds of the beam are gradually brought to the proper depth without endangering the rupture of the metal, which is unavoidable when the corrugation of folds of any considerable depth is effected by rollers alone.

The rolls (A and B) as shown in the drawing are made to match together, in such manner as to leave spaces (a, b, c, d) between them, corresponding in length to the width of the plate to be corrugated. The spaces are all of a length measured in the line of their sinuosities, the several folds becoming nearer each other just in proportion as they increase in depth so that the distance between the opposite sides of the beam measured in a straight line is least

when the folds are deepest, and greatest 55 while the corrugations are shallowest, the beam in this way diminishing in width as it increases in depth. The upper and lower rolls are in outline the counterpart of each other so that the openings between them are 60 of uniform depth and just equal to the thickness of the plate of which the beam is to be made. In rear of these rolls a crimping die is placed which consists of two blocks with grooves (l, m, n, o) across them, opposite 65 and on a level with the openings (a, b, c, d) between the rolls (A, and B). These grooves at the end next the rolls are bell-mouthed to facilitate the entrance of the plate between them, while their transverse 70 curvature within the bell-mouth, corresponds to that of the openings between the rolls; these grooves however become gradually narrower and deeper, as they approach the opposite side of the die, so that when a 75 plate is forced through them from the rolls, its folds will be deepened, and brought nearer together in proportion to the degree of taper of the grooves. When the plate leaves the groove of the die, the depth of its 80 folds and their distance apart will correspond to the size of the opening in the rolls, adjacent to that through which it last passed, in order that it may enter therein freely, and be further crimped by being 85 forced through another groove of the die adjacent to the last it passed through. In this way the crimping is effected chiefly by the die. For the purpose of more readily passing the plate through the die, a pair of 90 rollers may be placed in rear of it to seize the protruding end, as it is forced through the die by the action of the rolls in front so that when the front rolls have lost their hold of the plate, its passage through the die may 95 be effected by the rolls in rear. Or one plate may be forced through the die after it leaves the rolls (A and B) by the succeeding plate which pressing against its end will drive it forward.

In case the die should be placed somewhat lower or higher at its rear side than the openings between the back rolls, the beams made by this arrangement would be arched. This effect would be produced still better by 100 curving the grooves in the die block so as to correspond to the arch or curvature in the beams which it is desired to make.

As the frame work in which the rolls are supported and adjusted is of the usual construction, I have not deemed it necessary to describe it particularly; and with regard to the construction of the crimping die, it is only necessary to say that it is made in two parts which meet in the plane of the grooves; the grooves forming the upper side of the die, are made in the under side of the upper half or block, and those forming the under side, in the upper side of the lower half or block; these two halves of the die are firmly bolted together, and to the bed frame of the rolls, so that during the operation the strain may not displace them.

What I claim as my invention and desire to secure by Letters Patent is—

The method herein described of forming corrugated metal beams by passing a plate of metal of the proper size through a series 20 of grooves between rolls, and through a series of crimping dies substantially as herein set forth.

In testimony whereof, I have hereunto subscribed my name.

R. MONTGOMERY.
